Roscoe C. Wilson and Benjamin S. Kelsey, Fairfield, and Oscar A. Swanson, Dayton, Ohio

Application October 22, 1935, Serial No. 59,175

Term of patent 3½ years

To all whom it may concern:

Be it known that we, Roscoe C. Wilson, Benjamin S. Kelsey and Oscar A. Swanson, citizens of the United States residing at Fairfield, Fairfield and Dayton, respectively, in the counties of Greene, Greene and Montgomery, respectively, and State of Ohio, have invented a new, original, and ornamental Design for a Midwing, Tandem Propeller, Pusher Monoplane, of which the following is a specification, reference being had to the accompanying drawing, forming part thereof, wherein:

Fig. 1 is a top plan view of an airplane showing our new design;

Fig. 2 is a front elevational view of the said airplane design; and

Fig. 3 is a side elevational view of said airplane design.

We claim:

The ornamental design for a midwing, tandem propeller, pusher monoplane, as shown.

In testimony whereof we affix our signatures.

ROSCOE C. WILSON.
BENJAMIN S. KELSEY.
OSCAR A. SWANSON.
